(Cl. D34—5)

FIG. 1.

FIG. 2.

FIG. 3.

FIG. 4.

FIG. 5.

FIG. 6.

FIGURE 1 is a top plan view of a game device or the like showing my new design;

FIG. 2 is an elevational view thereof, as seen by looking toward the lower end of FIG. 1;

FIG. 3 is a rear view thereof;

FIG. 4 is a cross-sectional view thereof, taken substantially along the line indicated by the arrows 4—4 in FIG. 1;

FIG. 5 is a side elevational view thereof, as seen by looking at FIG. 1 from the right; and

FIG. 6 is a top plan view of a second disc which is interchangeable with the disc seen in FIGS. 1 through 5.

The dominant features of my design reside in the portions shown in full lines.

I claim:

The ornamental design for a game device or the like, substantially as shown and described.
